UNITED STATES PATENT OFFICE.

CHARLES W. HOTTMANN, OF PHILADELPHIA, PENNSYLVANIA.

DRYING APPARATUS.

1,302,165.

Specification of Letters Patent. Patented Apr. 29, 1919.

Application filed December 8, 1917. Serial No. 206,344.

To all whom it may concern:

Be it known that I, CHARLES W. HOTTMANN, a citizen of the United States, residing in the city and county of Philadelphia, State of Pennsylvania, have invented a new and useful Drying Apparatus, of which the following is a specification.

My present invention relates to a drying apparatus which while not limited to such use is especially adapted to be employed to effect the removal of the moisture from fat and meat scraps so that such material will be in proper condition to be placed in the oil press in order that the oil can be recovered from material of this character.

In devices heretofore employed for this purpose, it has been customary to arrange a steam jacket exteriorly of the container in which the material is placed, the result of which is that not only is a very large amount of heat lost due to radiation, but the portions of the material farthest removed from the action of the steam do not have sufficient moisture removed therefrom. It is also uncomfortable for the workmen to actuate machines constructed in this manner due to the intense heat which radiates into the room.

It is a purpose of my present invention to devise a novel construction and arrangement of a drying apparatus which will utilize a minimum amount of the drying agent, such as for example, steam or hot air, and which will enable one to remove uniformly from the mass of material the water which is present.

With the above in view, my invention in its broad and generic scope comprises a plurality of cylinders or their equivalents, between which is formed a chamber to receive the material to be dried or treated, while the inner cylinder is provided with means to cause a circulation therethrough of any desired type of fluid.

It further consists of a novel construction and arrangement of cylinders, a novel manner of supporting them, and a novel construction for effecting the removal of any gases which may be present in the chamber in which the material is placed.

It further consists of a novel construction and arrangement of a plurality of cylinders having baffles disposed therein and novel means to cause said cylinders to rotate in unison.

Other novel features of construction and advantage will hereinafter more clearly ap-

pear in the detailed description of the invention.

For the purpose of illustrating my invention, I have shown in the accompanying drawings a typical embodiment of it which is at present preferred by me, since this embodiment will give in practice satisfactory and reliable results, although it is to be understood that the various instrumentalities of which my invention consists can be variously arranged and organized and that my invention is not limited to the precise arrangement and organization of these instrumentalities as herein shown and described.

Figure 1 represents, in side elevation, a drying apparatus embodying my invention.

Fig. 2 represents a section on line 2—2 of Fig. 3.

Fig. 3 represents an end elevation of my device.

Fig. 4 represents a section on line 4—4 of Fig. 1.

Similar numerals of reference indicate corresponding parts.

Referring to the drawings:

1 designates foundation parts which are in the form of cradles or blocks which are provided with oppositely disposed rollers 2 which engage the bands or bearing rings 3, which latter carry the gears 4. The gears 4 are in mesh with the driving pinions 5 fixed to a shaft 6 journaled in the foundation parts 1. The driving shaft 6 is provided with a pulley 7 in order to adapt it to be connected with any desired driving motor or source of power. The bearing rings 3 are fixed to an outer cylinder 8, the ends of which extend over the flanged rings 9 which are provided with a series of ports 10 opening laterally through the rings and the arrangement of which will be best understood by reference to Fig. 4. The outer periphery of the member 9 is recessed to form a shoulder 11, with which the juxtaposed end of the cylinder 8 contacts.

12 designates an inner cylinder which forms with the outer cylinder 8 a chamber 13 to receive the material which is to be treated. The inner cylinder 12 forms a chamber 14 to receive the agent or medium which is to be employed, such as for example, steam or heated air, and to this end, each end of the cylinder 12 is closed by means of a cap 110 15 comprising a disk having connected therewith an annular band which is secured in

any desired manner to the inner periphery of the cylinder 12.

16 designates stuffing boxes and through one of these stuffing boxes extends an inlet 5 pipe 17 which serves as a means to introduce the drying medium, for example, into the chamber 14. This inlet pipe 17 is provided with a controlling valve 18 and is carried by a bracket 19 secured to an end plate 20, 10 which latter is provided with the supporting standards 21. An end plate is employed at each end of the machine and these plates are connected by stay rods 22. Each end plate 20 is provided preferably at its upper end 15 with a discharge passage 23, as will be readily understood by reference to the figures of the drawings.

It will be seen that when a port 10 has been moved into the position of the upper 20 ports 10, seen in Fig. 2, the upper portion of the chamber 13 is in communication with the discharge passage 23, so that any gas or fumes may freely pass from the chamber 13. The stuffing box 16 at the discharge end 25 of the chamber 14 is provided with a discharge conduit 24 carried by a bracket 19 and extending through the stuffing box 16 and its inner end is downwardly deflected as at 25 so that it will terminate in proximity to the lower end of the chamber 14, so 30 that any water condensed in the chamber 14 will be carried away through the conduit 24. The outer periphery of the inner cylinder 12 is provided with a desired number of longitudinally extending baffle plates 26, see Figs. 35 2 and 4, and the inner periphery of the outer cylinder 8 is provided with a desired number of longitudinally extending baffle plates 27. These baffle plates can be arranged in 40 different ways, but I have preferred to show the baffle plates 27 disposed between two of the baffle plates 26. The outer cylinder or 45 drum 8 is provided with a desired number of openings 28 which are controlled by doors 29, which as illustrated are hinged to the outer cylinder. For convenience of illustration, these doors have been shown in line with each other, but it is to be understood that it is within the scope of my invention 50 to locate these doors in any desired position or positions on the cylinder 8.

In the operation of my invention, the driving shaft 6 is caused to revolve in any desired manner, and the pinions 5 intermeshing with 55 the gears 4 cause the cylinder 8 to revolve and as this cylinder 8 is connected to the inner cylinder 12, these two cylinders rotate in unison. It will be understood that prior to the revolution of the driving shaft 6, the 60 material has been placed into the chamber 13 through the openings 28 and the doors 29 closed and secured in any desired manner. The valve 18 is opened and the steam or other medium passes through the inlet pipe 65 17 into the chamber 14 and is withdrawn

together with any water of condensation through the conduit 24. The fat containing meat within the chamber 13 is carried around with the drums due to the provision of the baffles and as portions of it are moved upwardly toward the top of the chamber 13, such portions slide backwardly toward the bottom of the chamber and are heated due to the heat radiating through the inner cylinder. By such construction, the water contained in the material is removed and passes off in the form of vapor through the ports 10, when such ports are in register with the discharge ports 23. After the material has been dried in this manner, the driving shaft 80 is stopped and the material is removed through the openings 28 for further treatment.

Assuming that the material as described has been acted upon, it is placed in an oil 85 press and the oil removed, it is then returned to the chamber 13 for further drying and is then again pressed to remove any remaining oil.

In accordance with my present invention, 90 the medium introduced through the pipe 17 passes into an inner cylinder so that a minimum amount of medium is necessary to produce the desired results.

It will now be apparent that I have devised a novel and useful drying apparatus, which embodies the features of advantage enumerated as desirable in the statement of the invention and the above description, and while I have, in the present instance, shown and described a typical embodiment of it which will give in practice satisfactory and reliable results, it is to be understood that this embodiment is susceptible of modification in various particulars without departing from the spirit or scope of the invention or sacrificing any of its advantages.

Having thus described my invention, what I claim as new and desire to secure by Letters Patent, is:—

1. In a drying apparatus, in combination, anti-friction devices, an outer cylinder supported on said anti-friction devices, an inner cylinder connected with said outer cylinder and forming therewith a chamber to receive material, end members closing the ends of said chamber and provided with a series of ports, a stationary member having discharge passages with which said ports are brought into register during the revolution of said cylinders, means to revolve said cylinders, and means to pass fluid through said inner cylinder.

2. In a drying apparatus, in combination, an outer cylinder, gears thereon, a driving shaft intergeared with said gears to rotate said cylinder, an inner cylinder, end members coöoperating with said cylinders to form a chamber therebetween and provided with ports, stationary members having discharge

passages with which said ports are brought into register during the revolution of said cylinders, means to close the ends of said inner cylinder, and means to pass a fluid 5 through said inner cylinder.

3. In a drying apparatus, in combination, an inner and an outer cylinder, end members connecting said cylinders to form a chamber and provided with ports, closures for the 10 ends of said inner cylinder, an inlet pipe extending through one of said closures and discharging into said inner cylinder, an outlet pipe extending through the other of said closures into said inner cylinder, means to close said ports except when they are at a predetermined position, and means to revolve said cylinders.

4. In a drying apparatus, an inner and an outer cylinder forming between them a chamber to receive the material, means to close the 20 ends of said cylinder, means to introduce a drying means into said inner cylinder, the closing means for said outer cylinder having ports therethrough and stationary means 25 having ports to communicate with the ports in said closing means during the revolution of said cylinders, and means to revolve said cylinders.

5. In a drying apparatus, an inner and an 30 outer cylinder having a chamber between

them to receive the material, closures for the ends of said inner cylinder, means to pass a drying medium into said inner cylinder, closures for said chamber, each of which is provided with a discharge port, means to 35 permit the fumes from said chamber to exhaust from said discharge ports when the latter are in a predetermined position, and means to simultaneously revolve said cylinders. 40

6. In a drying apparatus, an inner and an outer cylinder spaced from each other to form therebetween a chamber to receive the material, longitudinally extending baffles carried by said inner cylinder and extending 45 outwardly therefrom, longitudinally extending baffles carried by said outer cylinder and extending into said chamber, flanged rings connected with said inner and outer cylinders and having ports communicating with 50 said chamber, means at the end of said chamber to communicate with said ports, means to pass a drying medium into said inner cylinder, and means to revolve said cylinders. 45
